EDUCATIONAL SPELLING APPLIANCE OR
SIMILAR ARTICLE

Waldemar C. Rieck, Douglaston, N. Y.

Application August 23, 1951, Serial No. 16,413

Term of patent 14 years

(Cl. D25—1)

To all whom it may concern:

Be it known that I, Waldemar C. Rieck, a citizen of the United States, residing at Douglaston, county of Queens and State of New York, have invented a new, original, and ornamental Design for an Educational Spelling Appliance or Similar Article, of which the following is a specification, reference being had to the accompanying drawing, forming part thereof, in which,

Fig. 1 is a front elevational view of an educational spelling appliance or similar article, showing my new design;

Fig. 2 is a rear elevational view thereof, with the sides in a different position;

Fig. 3 is a side elevational view thereof; and

Fig. 4 is an enlarged section on the line 4—4 of Fig. 1 of a portion thereof.

A portion of the appliance is lined to indicate transparency.

I claim:

The ornamental design for an educational spelling appliance or similar article, as shown and described.

WALDEMAR C. RIECK.
